UNITED STATES PATENT OFFICE.

FRANK P. NOE AND SETH M. GOODER, OF CHICAGO, ILLINOIS.

METHOD OF CONSTRUCTING CONCRETE WALLS IN DEEP TRENCHES.

Application filed January 13, 1926. Serial No. 80,905.

In some localities, great difficulties are encountered in building concrete walls at a considerable depth as, for example, for sub-basements, because the great amount of 5 bracing necessary for the shoring at opposite sides of the trenches and the problems involved in securing effective bracing without leaving defective walls when the same are poured.

10 The object of the present invention is to produce a simple, novel and comparatively inexpensive method of shoring the sides of such trenches by means, a portion of which will remain in the finished wall, without 15 causing structural weakness in the wall and without leaving or permitting afterwards to be formed, openings through which leakage may occur.

15 The various features of novelty whereby 20 our invention is characterized will herein-after be pointed out with particularity in the claims; but, for a full understanding of our invention and of its objects and advantages, reference may be had to the following detailed description taken in connection with the accompanying drawings, 25 wherein:

Figure 1 is a vertical transverse section through the bottom of a trench, after a 30 wall has been poured therein, and before removal of such elements as are to be removed after the completion of the wall; Fig. 2 is a vertical section through a portion of the trench and wall, on a larger 35 scale than Fig. 1; Fig. 3 is a section taken approximately on line 3, 3 of Fig. 2; and Fig. 4 is a view similar to Fig. 3, showing the finished wall.

40 Referring to the first three figures of the drawings, A and B represent horizontal lagging placed at opposite sides of a trench as the same is being dug; the trench being considerably wider than the thickness of the wall to be produced. The lagging A 45 constitutes the form for one side of the wall and, spaced apart therefrom a distance equal to the desired thickness of the wall, is a second vertical wall form C.

50 What may be termed the trench linings, made up of the horizontal lagging at opposite sides of the trench, are held apart by numerous adjustable struts preferably arranged in vertical and horizontal rows from one end of the trench to the other. Each 55 strut is made of a comparatively thin steel pipe 1, open at the ends, somewhat longer

than the thickness of the wall to be produced, and having in one end a head 2 that constitutes a nut through which passes a jack screw 3. On the jack screw, outwardly 60 beyond the head, is an enlargement 4 containing a hole 5 into which may be inserted a rod or lever for turning the screw. Swiveled to the part 4 is a foot 6. The steel pipes are preferably arranged in groups of 65 two, three, or more, conveniently by setting them into the troughs of short metal channels 7, constituting waler adapted to extend vertically across the lagging or one side of the trench. In the arrangement shown, 70 each channel has thin metal plates 8 in the form of discs secured within the trough to the web; the spacings between the centers of the discs being the same as the spacings between the jacks. The discs may conveniently be fastened to the channels by rivets 9. These discs fit into the adjacent ends of 75 the jacks and prevent displacement of the jacks. The jack screws are made short as compared to the length of the pipes, so that when the screws have entered the pipes as far as they will go, there will be a considerable free space between the ends of the screws and the ends of the pipes that are engaged with the channels. This free space 80 is filled with concrete, as indicated at 10 in Fig. 3. Around each pipe is placed a block of wood 11, at such a point that the distance from its outer face to the outer face of the web of the channel is equal to the 85 thickness of the wall to be produced.

As the excavation of the trench progresses, the lagging is placed in position and the vertical rows of struts are started, each row being formed by placing one short channel 90 section directly below the overlying section, the feet at the opposite ends of the struts being engaged with waler 12 arranged vertically across the lagging B. The jack screws are turned until they exert sufficient 95 pressure on the linings for the trench. After the inner wall form C has been set up, the space between it and the lagging A is filled with concrete, as indicated at 14.

After the wall has set, the inner wall form 105 and the blocks 11 are removed, the removal of these blocks leaving cavities, one of which is indicated in dotted lines at 17 in Fig. 4, around each pipe in the exposed face of the wall. The pipes are then cut off within the 110 recesses, namely inwardly of the plane of the exposed face of the wall. The spaces

in the pipes, not already filled with concrete, as well as the recesses remaining upon the removal of the blocks, are filled with concrete, as shown in Fig. 4. After the wall 5 has been finished, as just described, it consists of a solid body of concrete containing thin steel pipes, completely surrounded by the concrete and completely filled with concrete. The presence of the pipes does not 10 impair the mechanical strength of the wall and does not cause, or permit later to be formed, openings through which water can pass. It will be seen that, by means of our invention, trenches in the most unstable materials 15 may be successfully shored so that a perfect wall may be poured in the same, without ultimate loss of any part of the apparatus excepting comparatively inexpensive pipe sections and the channels to which they 20 are attached, the jack screws and heads being recovered for further use.

In order to reduce the cost of leaving parts of the jacks in the completed wall as low as possible, the heads of the jacks are prefer- 25 ably set loosely into the ends of the pipes, so that the machined parts of the jack may be lifted out of the pipes before the latter are burned off. In the arrangement shown, each head has on the underside a lug 15 that 30 enters a notch 16 in the outer end of the pipe to which the head is fitted; thus interlocking the head and body of the jack against relative rotation.

While we have illustrated and described 35 with particularity only a single preferred form of our invention, we do not desire to be limited to the exact structural details thus illustrated and described; but intend to

cover all forms and arrangements which come within the definitions of our invention 40 constituting the appended claims, even though such forms and arrangements do not include each and every novel feature of our invention.

We claim:

1. The method of producing a wall in a trench, which consists in lagging the trench at the sides, setting walers across the lagging, placing between opposed walers screw jacks having body members in the 50 form of thin-walled pipes, erecting a wall form in the trench to cooperate with the lagging at one side to afford a space for the wall to be formed, pouring concrete into said space, and then cutting off the portion 55 of the pipes projecting from the wall after the concrete has set.

2. The method of producing a wall in a trench, which consists in lagging the trench at opposite sides, placing across the trench 60 screw jacks having body members made of long thin pipes filled at one end with concrete and having jack screws at the other end, erecting in the trench a wall form forming with the lagging adjacent to the filled 65 ends of the pipes a space for the wall to be poured, pouring concrete into said space, removing the wall form after the concrete has set, cutting off the projecting ends of the pipes, and filling the free space within the 70 pipes with concrete.

In testimony whereof, we sign this specification.

FRANK P. NOE.
SETH M. GOODER.
